BURNER

Ralph M. Hardgrove, Westfield, N. J., assignor,
by mesne assignments, to The Babcock &
Wilcox Company, Newark, N. J., a corpora-
tion of New Jersey

Application August 14, 1930, Serial No. 475,155

Renewed September 6, 1934

13 Claims. (Cl. 122—235)

This invention relates to a burner which is especially useful for burning finely divided solid fuel, such as pulverized coal.

The invention will be understood from the description in connection with the accompanying drawings in which Fig. 1 is a vertical section through an illustrative embodiment of the invention, taken on the line 1—1 of Fig. 3; Fig. 2 is a view from within the furnace of the structure shown in Fig. 1; Fig. 3 is a plan view partly in section showing the burner; and Fig. 4 is a vertical section taken on the line 4—4 of Fig. 1.

In the drawings, reference character 1 indicates a furnace having a series of transversely spaced vertically disposed tubes 2 extending along one of its vertical walls. The tubes 2 have their ends connected to a header outside of the furnace and may have water or other cooling fluid circulated through them in the well known way. The tubes are covered with blocks 4 at their furnace sides to provide a continuous wall. Some of the blocks 4 are omitted to provide a horizontally elongated rectangular burner port across which the tubes 2 extend in uniformly spaced relation. A pulverized fuel burner is arranged to discharge pulverized fuel and combustion air through the intertube spaces of the burner port. The fuel burner comprises a downwardly inclined distributing conduit 5 for pulverized fuel and primary air which tapers vertically and flares horizontally to its lower end which extends across substantially all of the tubes 2 within the burner port.

The conduit 5 is connected at its outer and upper end to a supply connection 6 provided with a sloping impact plate 7 against which the mixture of air and pulverized fuel from any convenient source impinges so that the mixture will be spread out laterally and substantially uniformly distributed in the conduit 5. An outlet or nozzle section 8, preferably a metal casting, is detachably connected to the exit end of the conduit 5. The outlet section 8 extends the full width of the conduit 5 and is provided with diverging upper and lower walls 8' having curved recesses therein fitting closely against the tubes 2 to provide good thermal contact therebetween and thus maintain the section 8 at a satisfactory operating temperature by preventing it from being overheated by radiant heat from the furnace. The portions of alternate tubes 2 within the limits of the outlet section 8 have crescent shaped shields 8a, as shown in Fig. 3, along their outer sides. The described burner parts and tubes jointly define a series of transversely spaced vertically elongated

fuel nozzles discharging through the intertube spaces of the burner port.

The portions of the intertube spaces above and below the outlet section 8 serve as secondary air inlet ports 10 and 11 respectively. The lower air port 11 is of greater cross-sectional area than the corresponding upper port 10 permitting more air to be introduced below the entering fuel and primary air stream than above it. The introduction of a greater quantity of air below the fuel stream is generally desirable as there is a better resultant mixture secured as the fuel streams are discharged downward while the tendency for the heated air is to rise toward the furnace outlet. In this way there is less possibility of air short-circuiting to the furnace outlet before coming in contact with the fuel and there is less possibility of the coarse fuel particles that are discharged dropping to the furnace floor or not coming into contact with the proper amount of combustion air before leaving the furnace.

Drip ledge blocks 9 are mounted on the wall cooling tubes 2 directly above the upper secondary air ports 10 with their side towards the furnace sloping so that they extend inwardly a short distance into the furnace. These blocks provide a ledge projecting out from the plane of the burner wall from which the molten slag, which runs down the wall, may drip and therefore obviates plugging up either the subjacent fuel nozzles or the secondary air ports 10 and 11.

Angle-irons 12 and 13 are mounted on and extend along the outside of the furnace wall and are connected to brackets 14 on the conduit 5 by means of turnbuckle rods 15 to hold the conduit 5 and outlet section 8 in position relative to the furnace wall.

A row of deflecting blocks 16 is provided along the furnace side of the tubes 2 opposite the fuel nozzles. These blocks 16 may be held in place against the tubes 2 by means of U-bolts 17 extending around the shields 8a. The blocks 16 are provided with curved surfaces to fit against the tubes and with countersunk openings 19 for nuts on the ends of the U-bolts 17. Heat conducting cement is preferably placed between the curved surfaces and the tubes 2 to secure good thermal contact. The sides of the blocks 16 toward the fuel nozzles are rounded, as indicated at 20, to divide the corresponding streams of incoming fuel into two sections, one inclined upwardly and the other downwardly, so that these streams of fuel will be struck by the air entering through the ports 10 and 11 substantially at right angles. The blocks 16 are shaped to divide each

stream of fuel into two unequal portions and deflect the larger portion downwardly into the furnace. Adajacent upper fuel stream portions tend to merge after leaving the deflector blocks into a substantially continuous sheet extending the full width of the burner port. The lower fuel stream portions similarly form a lower sheet of fuel.

By maintaining the blocks 16 and the outlet section 8 in a cool condition, the pulverized fuel is prevented from depositing and coking on them. Such a deposit would not only interfere with the proper functioning of the burner with respect to the discharge of fuel but this coking would cause rapid destruction of the burner metallic parts.

Dampers 23 are pivoted at 24 to a bracket 25 above the air ports 10 and dampers 26 pivotally attached at 27 to arms 28 pivoted at 29. Rods 30 are provided for operating the dampers 23 and 20 26, so that the secondary air inlets 10 and 11 can be partially or entirely closed.

A secondary air casing 31 surrounds the burner port and described burner parts and may be supplied with air under pressure in any convenient 25 way. The casing 31 is supported on the furnace wall tubes by means of angle bars so that it and the conduit 5 will move up and down with the tubes 2 as they expand and contract due to changes in temperature.

30 A tubular member 32 for a lighter may extend through the air casing 31 into proximity to the fuel nozzles for lighting off the burner. The outlet of the tubular member 32 is located at or near the center of the burner port, as shown in 35 Fig. 2, so that the lighter flame will be directed beneath the middle of the lower set of coal and air streams. A sleeve 33 having air ports 34 is mounted near the lower end of the tubular member 32 so that secondary air from the casing 31 40 may be allowed to flow through the tubular member 32 when the burner is in normal operation, thereby keeping the tubular member 32 cool and also preventing pulverized coal or fine ash or slag from finding its way back into this tube from 45 the opening in the furnace. The sleeve 33 can be rotated by a rod 35 that extends to the outside of the casing 31 through a pair of spaced cams 36 on the rod fitting between and moving spaced pairs of lugs 37 on the sleeve 33 so that the air 50 openings 34 can be brought into register with corresponding openings through the wall of the tubular member 32, or the sleeve 33 can be turned to decrease the amount of air entering or shut it off entirely.

55 With the described burner construction, the flame of the burning fuel is projected into the furnace somewhat downwardly, which direction is especially useful where such burners are installed on opposite sides of the furnace as this 60 will result in a very thorough mixing of the products of combustion and air. Also, by inclining the burner fuel conduit parts downwardly, the danger of fuel particles lying or lodging therein is obviated, even when the velocity of the incoming 65 air is small. An inclination of about 16° from the horizontal has been found to be quite satisfactory in operating a burner of this type, although other inclinations may be used.

Certain subject matter disclosed herein is disclosed and claimed in my prior copending application Serial No. 387,214, filed August 20, 1929.

I claim:

1. In a furnace wall, upwardly disposed spaced tubes, a burner having a nozzle portion extending 75 transversely across a plurality of said tubes to

discharge streams of fuel and air therebetween, and means in thermal contact with said tubes to divide each stream of fuel and air from said burner into two unequal sheets and project the greater sheet downwardly within the furnace. 5

2. In a furnace wall, upwardly disposed spaced tubes, a burner having a nozzle portion extending transversely across a plurality of said tubes to discharge streams of fuel and air therebetween, and a deflecting block in thermal contact with said tubes in front of said nozzle portion to divide each stream of fuel and air from said burner into two sheets, said deflecting block having a greater extent downwardly of the furnace than upwardly in order to project the greater 10 portion of the fuel and air stream downwardly within the furnace. 15

3. In a furnace wall, upwardly disposed spaced tubes, a burner downwardly inclined to the plane of the wall, said burner having a nozzle 20 portion extending transversely across a plurality of said tubes to discharge streams of fuel and air therebetween, and a deflecting block in thermal contact with said tubes in front of said nozzle portion to divide each stream of fuel and air 25 from said burner into two sheets, said deflecting block having a greater extent downwardly of the furnace than upwardly in order to project the greater portion of the fuel and air stream downwardly within the furnace. 30

4. In a furnace wall, upwardly disposed spaced tubes, a burner downwardly inclined to the plane of the wall, said burner having a nozzle portion extending transversely across a plurality of said tubes to discharge streams of fuel and air there- 35 between, and a deflecting block in thermal contact with said tubes in front of said nozzle portion to divide each stream of fuel and air from said burner into two sheets, said deflecting block having a greater extent downwardly of the fur- 40 nace than upwardly in order to project the greater portion of the fuel and air stream downwardly within the furnace, in combination with means to cause one stream of air to enter the furnace through the furnace wall above said nozzle portion and a larger stream of air to enter the furnace beneath said nozzle portion. 45

5. In combination, a vertical furnace wall, a fuel burner arranged to discharge a stream of fuel through said wall, means for dividing said fuel stream into two unequal portions and deflecting the larger portion downwardly within the furnace, an air port in said wall above said fuel burner, and an air port in said wall below said fuel burner of greater cross-sectional area 55 than said first named air port.

6. In combination, a vertical furnace wall, a fuel burner arranged to discharge a stream of fuel through said wall, means for dividing said fuel stream into two unequal portions and deflecting the larger portion downwardly within the furnace, an air port in said wall above said fuel burner, an air port in said wall below said fuel burner of greater cross-sectional area than said first named air port, and means for introducing 60 air for combustion through said air ports in streams impinging on corresponding portions of said fuel stream. 65

7. In combination, a vertical furnace wall, a fuel burner arranged to discharge a stream of fuel through said wall, means for dividing said fuel stream into two unequal portions and deflecting the larger stream downwardly within the furnace, air ports in said wall above and below said fuel burner, means for introducing air for 70 75

combustion through said air ports in streams impinging on corresponding portions of said fuel stream, and damper means for controlling each of said air ports.

5 8. In combination, a vertical furnace wall comprising a pair of vertically arranged transversely spaced cooling tubes, a fuel burner arranged to discharge a fuel stream between said tubes, and means in thermal contact with said tubes for 10 dividing said fuel streams into two unequal portions and deflecting the larger portion downwardly at the inner side of said furnace wall.

15 9. In combination, a vertical furnace wall comprising a pair of vertically arranged transversely spaced cooling tubes, a fuel burner having a downwardly inclined conduit terminating in a nozzle arranged to discharge a fuel stream between said tubes, and means for dividing said fuel stream into two unequal portions and deflecting the larger portion downwardly at the 20 inner side of said furnace wall.

25 10. In combination, a vertical furnace wall having a fuel burner port formed therein and a series of vertically arranged horizontally spaced cooling tubes extending across said burner port, a fuel burner having a downwardly inclined conduit terminating in a nozzle portion extending across said tubes and arranged to discharge fuel streams between said tubes, means in thermal 30 contact with said tubes for dividing each fuel stream into two portions, and said burner port providing openings for the passage of combustion air between said tubes above and below said nozzle portion.

35 11. In combination, a vertical furnace wall comprising a pair of vertically arranged trans-

versely spaced cooling tubes, a fuel burner arranged to discharge a fuel stream between said tubes, means in thermal contact with said tubes for dividing said fuel stream into two unequal portions and deflecting the larger portion downwardly, openings for the passage of combustion air between said tubes above and below said nozzle, and the opening below said nozzle being of greater area than that above said nozzle.

12. In combination, a furnace wall, a fuel burner arranged to discharge a fuel stream through said wall, an air box surrounding said fuel burner, means for discharging combustion air from said air box through said wall adjacent the point of fuel discharge and in a direction to commingle with the fuel stream adjacent said wall, a lighting torch conduit extending through said air box and opening through said wall adjacent the point of fuel discharge, and said conduit having an opening therein for the entrance 20 of air from said air box.

13. In combination, a furnace wall having a series of vertically arranged spaced cooling fluid tubes, a fuel burner arranged to discharge a fuel stream between said tubes, an air box surrounding said fuel burner, means for discharging combustion air from said air box between said tubes adjacent the point of fuel discharge and in a direction to commingle with the fuel stream adjacent said wall, a lighting torch conduit extending through said air box and opening between said tubes adjacent the point of fuel discharge, and means forming an adjustable opening for the passage of air from said air box into 30 said conduit.

RALPH M. HARDGROVE.
